FOLDABLE FRAME FOR SCREENS

Allan V. Ditty, Grosse Pointe, Mich., assignor, by
mesne assignments, to Arthur J. Bradford, Chi-
cago, Ill.

Application May 26, 1945, Serial No. 596,023

2 Claims. (Cl. 160—24)

1

This invention relates to collapsible screens and particularly to a foldable frame for projection screens for use with optical projection apparatus.

One object of this invention is to provide a collapsible screen with a foldable frame having an extensible and collapsible support, the opposite portions of which are mechanically synchronized so as to be extended and retracted in unison.

Another object is to provide a foldable frame for a screen supported by pivoted arms which are mechanically interconnected by a mechanism which positively guarantees their being extended and retracted in synchronism.

Another object is to provide a foldable frame for a screen as set forth in the preceding object wherein means is provided by the same mechanism for holding the arms in their extended positions without danger of accidental collapse.

Another object is to provide a foldable frame for a screen having a flexible sheet capable of being wound upon a roller and having a supporting bar along one edge connected to pivoted arms which are mechanically interconnected to be extended and retracted in unison.

Another object is to provide a foldable frame for a screen as set forth in the preceding object wherein the arms and bar are adapted to be received in the housing which contains the roller.

In the drawings:

Figure 1 is a rear elevation of a preferred embodiment of the collapsible frame for a screen of the present invention, with a portion of the housing broken away to expose the lower ends of the supporting arms, and with the screen extended.

Figure 2 is a right-hand side elevation of the screen shown in Figure 1.

Figure 3 is a rear elevation similar to Figure 1, but with the screen retracted and collapsed.

Figure 4 is a horizontal section through the screen of Figure 1 taken along the line 4—4 therein.

Figure 5 is a fragmentary vertical longitudinal section through the housing with the screen extended, taken along the broken line 5—5 in Figure 4.

Figure 6 is a vertical cross-section through the screen housing with the screen extended, taken along the line 6—6 in Figure 1.

Figure 7 is a cross section similar to Figure 6, but with the screen retracted into its housing.

Figure 8 is a left-hand end elevation of the screen housing of Figure 1 with the screen extended.

2

Figure 9 is a horizontal section through the pivotal connection of the supporting arms, taken along the line 9—9 in Figure 1.

Figure 10 is a vertical section through the pivotal connection of one set of the supporting arms taken along the line 10—10 in Figure 2.

In general, the invention consists of a flexible sheet member which is wound upon a roller in a housing. The sheet member is provided with a supporting bar along its upper or free edge. To this bar are secured a pair of downwardly extending arms pivotally connected to the upper ends of a pair of upwardly extending arms pivotally mounted on a bracket in the screen housing. The upper ends of the upper arms and the lower ends of the lower arms are interconnected by toothed gearing in such a manner that the two sets of arms will be extended and retracted in unison. When retracted, the pivoted arms fold downward into the housing as the screen is wound up on the roller, and the bar comes down on top of the housing.

Hitherto, it has been difficult to provide a collapsible screen wherein the opposite ends of the screen proper would always be extended to the same positions, thereby preventing wrinkles; and also wherein the extended screen would be rigidly supported without sagging and yet would be capable of instant retraction into a small housing. The screen of the present invention overcomes these previous difficulties, and solves the problem by providing a pair of sets of pivoted arms which are geared together to rise and fall in unison.

Referring to the drawings in detail, Figure 1 shows a preferred embodiment of the foldable frame for a screen having a box-like housing generally designated 10 with a screen member generally designated 11 capable of being wound upon a roller, generally designated 12 and sustained in its extended position by a supporting structure generally designated 13.

The housing 10 is in the form of a box having a bottom 14, front and rear walls 15 and 16 (Figures 6 and 7), a top 17 and ends 18 and 19. The ends 18 and 19 are provided with apertures 20 from which tubular brackets 21 and 22 extend inwardly and are secured by rivets 23 to the ends 18 and 19. The bracket 21 is provided with an elongated hole 24 and the bracket 22 with a circular hole 25.

The holes 24 and 25 receive the correspondingly shaped end pins 26 and 27 respectively (Figure 5) of the roller 12. The pin 27 of circular cross-

section is inserted directly in the end cap 28 at one end of the roller whereas the pin 26 of elongated cross-section is at the end of a shaft 29 passing loosely through a bore 30 through the other end cap 31 and having an enlarged head 32 engaging an enlargement 33 at the end of the bore 30. The shaft 29 at its inner end is provided with a head 34 having a socket 35 for receiving the inner end of a spiral spring 36, which encircles the shaft 29 and has its opposite end secured in a socket 37 in the end cap 31. The end caps 28 and 31 are interconnected by a hollow tubular roller barrel 38 rigidly secured thereto as at 39.

The roller barrel 38 is provided with a longitudinal groove 40 (Figure 6 and 7 within which is anchored the inner edge 41 of the screen member 11, as by the retaining bar 42 secured to the roller barrel 38 as at 43. The opposite edge of the screen member 11 is wound around a tubular cross-bar 44 and secured to itself as at 45 (Figure 7) by a suitable adhesive or other means. Secured as at 46 to the center of the tubular cross-bar 44 is a bracket 47 which extends over the top of the cross-arm 44 and has a downwardly extending arm 48 forming a plate with apertures 49 (Figure 7) for receiving a pair of threaded studs 50. These studs 50 pass through apertures 51 in a pair of upper channel arms 52 forming the upper portions of the supporting structure 13. Each stud 50 within the channel portion of the channel arm 52 carries a quadrant gear 53 meshing with the quadrant gear 53 on the other stud 50 (Figure 1). The quadrant gears 53 are firmly secured to the channel arms 52 by the pins 54 passing through both.

The channel arms 52 are pivoted to the lower arms 55 by means of pivot pins 56 passing through apertures 57 in each pair (Figure 10). The channels in the channel arms 52 face inwardly toward one another, and the pivot pin holes 57 are so arranged that when the screen is extended to its fully raised position, the lower arms 55 move past the position of alignment with the channel arms 52 and come to rest against the lower back edges 58 of the channel arms 52. In this way the pivoted arms 52 and 55 are moved past dead center into self-sustaining positions.

The lower ends of the lower arms 55 are provided with bores 59 (Figure 6) for receiving a stud bolt 60 passing therethrough and through an aperture 61 in an angle bracket 62 secured as at 63 to the bottom 14 of the housing 10. The stud bolt 60 also passes through the side wall 16 of the housing 10 and is provided with lock nuts 64 and 65 on opposite sides thereof. Mounted on the stud bolt 60 and secured as at 66 to the lower arms 55 are two meshing gears 67 which operate in a similar manner to the quadrant gears 53 described above (Figure 5).

In operation, to extend the screen from its folded position of Figure 3 the operator pulls upward on the tubular cross-bar 44 of the bracket 47, causing the upper and lower arms 52 and 55 to move from the position of Figure 3 upwardly into the positions of Figure 1, meanwhile crossing the aligned position just prior to halting with each lower arm 55 coming to rest against the back lower edge 58 of each channel arm 52. As the arms 52 and 55 swing upwardly and their pivots 56 swing in arcs from the outer ends of the casing 10 (Figure 3) to the central positions of Fig. 1, the intermeshing teeth of the gears 53 and 67 drivingly interconnect the two

sets of arms 52 and 55 in such a manner that the arms move in unison.

Since the pivots 50, 56 and 60 are spaced laterally from each other, the cross bar 44 is supported, in effect, by a pair of rigid but foldable spaced pillars. The geared interconnection of the two sets of arms 52 and 55 prevents one set of arms from moving independently of the other set, hence the cross-bar 44 is raised and lowered by a linkage which causes it to move through successively parallel positions. As the screen member 11 is raised and unwound from the roller 12, the coil spring 36 (Figure 5) is wound up and stores up energy. This maintains the screen member 11 in a taut position. The screen member 11 is preferably made of a resilient material, such as white rubber, so that it is free from wrinkles and maintains itself in that condition.

To lower the screen member 11, the operator grasps the supporting structure 13 adjacent the pivots 56 and pushes the latter away from each other. The pivots 56 and arms 52 and 55 then move past their aligned position and downwardly into the folded position shown in Figure 3. Here again the intermeshing gears 53 and 67 cause the arms 52 and 55 to move downwardly in synchronism, causing the cross-bar 44 to move downwardly through successive parallel positions. The cross-bar 44 comes to rest immediately over the slot 68 in the top 17 of the housing 10, partially closing this slot. The screen is thus foldable into very compact form and is protected by the housing 10 against dust and damage.

While a specific embodiment of the invention has been described and illustrated, it will be understood that various modifications may be made within the scope of the appended claims without departing from the spirit of the invention.

What I claim is:

1. A foldable frame for a collapsible screen comprising a base, a cross bar spaced above said base, and two pairs of foldable uprights arranged adjacent one another and having their lower and upper ends pivotally connected to the central portions of said base and cross bar respectively, each of said uprights including a lower and an upper arm having a common pivotal connection to one another and disposed alongside one another in the folded position of said arms, said common pivot lying substantially at the outer extremity thereof, one of said arms having an extension overlapping the other arm beyond said common pivot and having an abutment engageable with said other arm at a location spaced away from said common pivot when said arms are extended, said common pivot and said abutment being disposed inwardly of a line joining the centers of the pivotal connections of the upright with the base and cross bar respectively when said frame is fully extended, thereby rendering said frame self-sustaining in its fully extended position.

2. A foldable frame for a collapsible screen comprising a base, a cross bar spaced above said base, and two pairs of foldable uprights arranged adjacent one another and having their lower end and upper ends pivotally connected to the central portions of said base and cross bar respectively, each of said uprights including a lower arm and an upper arm having a common pivotal connection to one another, one of said arms being of channel cross-section and the other arm being received within the channel portion thereof in the folded position of said arms, said common pivot lying substantially at the outer extremity

thereof, one of said arms having an extension overlapping the other arm beyond said common pivot and having an abutment engageable with said other arm at a location spaced away from said common pivot when said arms are extended, said common pivot and said abutment being disposed inwardly of a line joining the centers of the pivotal connections of the upright with the base and cross bar respectively when said frame is fully extended, thereby rendering said frame 10 self-sustaining in its fully extended position.
